GATE OPERATING MEANS

Philip Schnell, Hillside, N. J.

Application June 4, 1936, Serial No. 83,484

4 Claims. (Cl. 39—8)

My invention relates to improvements in gate latches.

One of the objects of my invention is to provide an improved construction for a latch adapted particularly for gates of the general type used in closing the entrance to the yard or grounds of places of business, institutions, and the like, and which can be controlled from a remote point by hydraulic apparatus to unlatch the gate and then open it, and then close the gate when desired so that it cannot be opened from the outside.

Another object of my invention is the provision of an improved construction for a gate latch of the character referred to which is relatively simple and inexpensive in construction, easy to install and reliable in operation.

Other objects and advantages will hereinafter appear.

For the purpose of illustrating my invention, an embodiment thereof is shown in the drawings, wherein—

Figure 1 is an elevational view, partly diagrammatic, showing my improved latch and the operating and control mechanism therefor, installed to actuate and control two complementary, swinging gates;

Fig. 2 is an enlarged fragmentary view taken from Fig. 1, showing the various parts of my improved latch in position to lock the gates;

Fig. 3 is an enlarged sectional view, the section being taken on the line 3—3 in Fig. 1;

Fig. 4 is a diagrammatic view, partly in section, of the hydraulic control and actuating apparatus; and

Fig. 5 is an enlarged sectional view, the section being taken on the line 5—5 in Fig. 1.

With reference to the drawings, the reference numerals 10 and 12 designate complementary gates supported for swinging movement from a closed position as shown in Fig. 1 to an open position.

Locking bolts 14 and 16 are carried by the gate 12 for movement into and out of locking position. The bolt 14 has a sliding fit in bracket or bearing members 18 fixed to the free edge of the gate 12, and the lower end of this bolt is received by a fixed socket 20 when in the locking position.

The bolt 16 is pivotally connected at one end thereof to the gate 12, at 22, and when in locking position as shown in Figs. 1 and 3, this bolt rests in U-shaped brackets 24 and 26 fixed respectively to the lower adjacent corners of the gates 10 and 12.

The bolt 16 is pivotally connected intermediate

its ends to the bolt 14 by a pin-and-slot connection 28 of conventional construction, so that when the bolt 14 is raised to unlock the gates, the bolt 16 is also raised out of locking position to permit the opening of gate 12 without opening the gate 10.

A member 30, in the form of a piston in a hydraulic cylinder 32, is connected to the gate 12 by a rod 34, a crosshead 36, a rod 38 and a second crosshead 40. The crosshead 36 slides on a fixed bar 42, and the crosshead 40 slides on a bar 44 fixed to the gate 12.

The crosshead 40 is connected by a link 46 to a block 48 slidable on the bar 44 between a bracket 50 and an element 52, both of which are carried by and fixed to the bar 44.

A link 54 is pivotally connected at one end thereof to the bolt 14 by a pin-and-slot connection 56 of conventional construction, and is pivotally connected intermediate its ends by a pin 58 to the bracket 50.

A relatively stiff tensioned spring 60 connects the other end of the link 54 to the fixed element 52.

A link 62 is pivotally connected at one end thereof to the slidable block 48 by a pin 64, and is pivotally connected by a pin 66 to the link 54 at a point between the pivotal connection 58 and the spring 60.

The arrangement and relation of the various parts are such that when the gates are closed and locked as shown in Fig. 1, the longitudinal axis 68 of the link 62 is slightly to the right of the vertical 70 to lock the link 54 against clockwise rotation about the pin 58. It will therefore be seen that the link mechanism comprising the links 54 and 62 has a dead-center position which is passed when these links are moved into their respective positions as shown in Fig. 1, which arrangement locks the bolts 14 and 16 against upward movement.

To open the gate 12, oil or other suitable liquid under pressure is admitted by the pipe 72 into the lefthand end of the cylinder 32. The piston 30 then starts to move from its first position at the lefthand end of the cylinder to a second position at the righthand end of the cylinder. As the piston 30 starts this movement, the block 48 is pulled to the right against the fixed element 52 so that the various parts are moved to their respective positions as shown in Fig. 2 to raise the bolts 14 and 16 out of their locking positions. As the piston 30 continues its righthand movement after the block 48 engages the fixed element 52, the gate 12 begins to swing open, and

reaches its full-open position as shown in dash lines in Fig. 3 when the piston 30 reaches the righthand end of the cylinder 32.

To close and lock the gate 12, liquid under pressure is admitted by a pipe 74 to the righthand end of the cylinder 32, whereupon the piston 30 starts to move from its second, righthand position to the first position at the lefthand end of the cylinder. The gate 12 thereupon is swung into its closed position, during which movement the tension of the spring 60 is sufficient to prevent lefthand movement of the block 48 away from the fixed element 52. The bolts 14 and 16, therefore, are held raised out of locking position, as the gate 15 is swung closed under the thrust exerted through the link 46.

At the instant the gate 12 reaches its closed position shown in Figs. 1 and 3, the various parts comprising the latch or lock are still in their respective positions as shown in Fig. 2. However, as the piston 30 continues its lefthand movement under the hydraulic pressure, the block 48 is forced to the left against the bracket 50 to cause the bolts 14 and 16 to drop into their locking positions as shown in Fig. 1.

From the foregoing it will be seen that the various parts or elements connecting the piston member 30 to the bolts 14 and 16 have a given amount of free-play which is taken up as the piston moves out of its first position, as shown in Fig. 1, and before the gate 12 starts to open.

It will be seen, further, that the links 54 and 62 and the various parts associated therewith, and which constitute part of the means connecting the piston member 30 to the gate 12, operate to raise the bolts 14 and 16 out of their locking positions when the block 48 moves over against the fixed element 52 as the piston member 30 moves to the right, and as the free-play in the mechanism is taken up.

The gate 10 is opened and closed by a hydraulic cylinder 74 and associated piston 76 connected to this gate through a rod 78, a crosshead 80 slideable along a fixed bar 82, and a rod 84 connecting the gate to the crosshead.

A valve 86 operates to admit oil or other liquid under pressure from a pump unit 88, into either end of the cylinder 32 and to connect the other end of the cylinder to a surge tank 90, from whence the liquid returns to the intake side of the pump.

Likewise, a valve 92 operates to admit the liquid under pressure into either end of the cylinder 74 and to connect the other end of this cylinder to the surge tank 90.

It will be seen from the connections shown in Figs. 1 and 4 that the gates 10 and 12 are caused to close when the valves 86 and 92 are moved to their respective righthand positions, as shown in Figs. 1 and 3.

It will be seen that when these valves are swung over to the left, the gates 10 and 12 are caused to open.

For the purpose of preventing opening of gate 10 before gate 12 has been unlatched and has started on its opening movement, a locking lever 94 is pivotally mounted at 96 and disposed with its ends in close proximity to the two valves. With the valves in the positions shown in Fig. 1, the end 98 of the lever 94 is held locked in a notch 100 in the valve 92, on account of engagement of the end 102 with the cylindrical surface of the valve 86. When the valve 86 is swung over to the left to open the gate 12, the end 102 is received by a notch 104 in this valve, whereupon the

end 98 can leave the notch 100 to permit swinging of the valve 92 over to the left to open the gate 10. It will be seen that the valve 86 is now locked on account of engagement of the end 98 with the cylindrical surface of the valve 92. It is therefore required that, in closing the gates, the valve 92 first be swung over to the right to start the gate 10 well on its closing movement before the valve 86 can also be swung over to the left to start closing movement of the gate 12. In this way, the two gates are always made to close and open in the proper sequence.

From the foregoing it will be seen that I have provided an improved construction for a latch which is particularly adapted for locking large, heavy gates, and which is adaptable to be controlled from a remote point by hydraulic apparatus to first unlatch the gates and then open them, and then close the gates and latch them when desired so that they cannot be opened from the outside by unauthorized persons.

While but one embodiment of my invention has been disclosed, it will be understood that various modifications such as in the size, shape and arrangement of the parts might be made without departing from the spirit of my invention or the scope of the claims.

I claim as my invention:

1. The combination with a gate supported for swinging movement from a closed position to an open position, of a locking bolt carried by said gate for movement into and out of locking position, a second locking bolt pivotally connected to said gate and to said first-named bolt and movable by the latter into and out of locking position, a member connected to said gate and movable from a first position to a second position with respect thereto to impart opening movement to said gate and movable from said second position to said first position to impart closing movement to said gate, means connecting said member and said bolts and having a given amount of free-play which is taken up as said member moves out of said first position and before opening movement is imparted to said gate, and means forming part of said connecting means and operating to move said bolts out of their respective locking positions as said member moves out of said first position; said second-named means comprising a bar carried by said gate, a crosshead slideable along said bar, and an element disposed between said member and said crosshead and fixed with respect to said bar to act as a stop for said crosshead when said given amount of free-play is taken up as specified.

2. The combination with a gate supported for swinging movement from a closed position to an open position, of a locking bolt carried by said gate for movement into and out of locking position, a member connected to said gate and movable from a first position to a second position with respect thereto to impart opening movement to said gate and movable from said second position to said first position to impart closing movement to said gate, means connecting said member and said bolt and having a given amount of free-play which is taken up as said member moves out of said first position and before opening movement is imparted to said gate, and means forming part of said connecting means and operating to move said bolt out of locking position as said member moves out of said first position; said second-named means comprising a bar carried by said gate, a crosshead slideable along said bar, an element disposed between said

member and said crosshead and fixed with respect to said bar to act as a stop for said crosshead when said given amount of free-play is taken up as specified, and link mechanism having a dead-center position and disposed when past such position in one direction to lock said bolt in the locking position thereof.

3. The combination with a gate supported for swinging movement from a closed position to an open position, of a locking bolt carried by said gate for movement into and out of locking position, a member connected to said gate and movable from a first position to a second position with respect thereto to impart opening movement to said gate and movable from said second position to said first position to impart closing movement to said gate, means connecting said member and said bolt and having a given amount of free-play which is taken up as said member moves out of said first position and before opening movement is imparted to said gate, means forming part of said connecting means and operating to move said bolt out of locking position as said member moves out of said first position; said second-named means comprising a bar carried by said gate, a crosshead slidable along said bar, and an element disposed between said member and said crosshead and fixed with respect to said bar to act as a stop for said crosshead when said given amount of free-play is taken up as specified; and spring means for holding said crosshead substantially at said fixed element during closing movement of said gate.

4. The combination with a gate supported for swinging movement from a closed position to an open position, of a locking bolt carried by said gate for movement into and out of locking position, a member connected to said gate and movable from a first position to a second position with respect thereto to impart opening movement to said gate and movable from said second position to said first position to impart closing movement to said gate, means connecting said member and said bolt and having a given amount of free-play which is taken up as said member moves out of said first position and before opening movement is imparted to said gate, means forming part of said connecting means and operating to move said bolt out of locking position as said member moves out of said first position; said second-named means comprising a bar carried by said gate, a crosshead slidable along said bar, and an element disposed between said member and said crosshead and fixed with respect to said bar to act as a stop for said crosshead when said given amount of free-play is taken up as specified, and link mechanism comprising links pivotally connected to each other and to said crosshead and to said bolt and having a dead-center position past which said mechanism operates to lock said bolt in the locking position thereof; and tensioned spring means connected at its ends to said fixed element and one of said links for holding said crosshead substantially at said fixed element during closing movement of said gate.

PHILIP SCHNELL.
